UNITED STATES PATENT OFFICE

LOUIS H. ZEUN, OF CATONSVILLE, MARYLAND, ASSIGNOR OF ONE-THIRD TO ALBERT W. ADT AND ONE-THIRD TO JOHN B. ADT, BOTH OF BALTIMORE, MARYLAND

TOBACCO STEMMING AND STRIPPING MACHINE

Application filed July 18, 1929. Serial No. 379,204.

This invention relates to apparatus for parting the blades and stems of tobacco leaves from each other, and with respect to its more specific features, to an automatically operating apparatus for controlling movements of the leaves and stripping the blades from the stems in a manner to recover a greater part of the blade in integral form largely free of all objectionable stem material.

One of the objects of the invention is the provision of a simple and practical machine for butting and stemming tobacco leaves and wherein the butting strippers and the stemming strippers may be made of relatively rigid and durable material, as steel, and are controlled to minimize, lessen or avoid stem breakage, and which will operate efficiently on the normal run of leaf without injurious jamming otherwise occasioned when stripping different size and different quality leaf controlled and stripped by automatic machinery.

Another object is the provision of a simple and efficient arrangement of butting strippers relative to stemming strippers wherein leaf movement due to stripping is generally rearward of the machine from a substantially straight path of the advancing leaf thus promoting a relatively small front to rear dimension of the machine without detracting from any length that may be desired or needed to effect stripping in an efficient manner.

Another object is the provision of a practical stripping mechanism including a stripper fork having movement promotive of operative engagement with the leaf preliminary to or along with its stripping movement.

Another object is the provision of a simple and practical association of a gang of butting strippers and a gang of stemming strippers, and in which the strippers of each gang are each adapted for stripping action separately from others, so that different stages of stripping operation on different individual leaves may be performed, simultaneously and on one leaf with regard to the other leaves.

Another object is the provision of a gang of stripper forks of rigid material, each fork adapted for stripping action separately from

the others and each fork having jam relieving movement separately from others.

Another object of the invention is the provision of a practical and simple form of stripper fork controlled for relieving jamming of the leaf therein and which may be utilized either as a butting stripper or a stemming stripper.

Another object is the provision of practical and improved stripping mechanism including a gang of stripper forks each adapted to yield to relieve jamming, and which may positively be actuated to relieve jamming if desired.

Another object is the provision of practical and improved stripping mechanism including stem drawing mechanism adapted to cooperate to stem without placing swerve transverse strain on the stems.

Another object is the provision of a practical, durable, and rugged construction of strippers and their controlling and actuating devices.

Another object is the provision of simple and practical mechanism adapted to center the stems in the stripping apertures of stripper forks.

Another object is the provision of practical mechanism for weakening leaf stems, so as to promote stemming.

Other objects are the provision of simple, practical and efficient mechanisms for controlling the leaf during the butting; for controlling the leaf during the stemming; for holding the leaf during butting; for separating the leaves from each other preliminary to being stripped; for feeding the raw leaf material to the stripping mechanisms; and for progressively advancing the leaf from the supply end to the discharge end of the machine.

Other objects of the invention will in part be obvious and will in part appear hereinafter.

The invention accordingly comprises the features of construction, combinations of elements, and arrangement of parts, which will be exemplified in the construction hereinafter set forth and the scope of the appli-

cation of which will be indicated in the claims.

For a fuller understanding of the nature and objects of the invention, reference should be had to the following detailed description taken in connection with the accompanying drawings, in which:

Fig. 41 is a vertical section through the cutter of Fig. 36;

Fig. 42 is a vertical, sectional detail through the upper series of leaf-advancing and gripping mechanism.

Referring now more specifically to the drawings, the frame of the machine includes a table 1 supported upon legs 2, braced by cross pieces 3. The table 1 may be made of wood and preferably has a slick upper surface, as for instance would be imparted by covering the upper face with a polished aluminum sheet. Uprising from the table 1 and firmly secured thereto, or to the legs 2, is an upper metal frame portion, or housing, generally indicated by the numeral 4. At 5 is the butt evener which may consist of a stationary plate of wood rising from the table 1 and adjustable in position laterally of the table.

Leaf-advancing mechanism

In the present embodiment of the invention, the tobacco leaves to be stemmed are supplied at the leaf-hand end of the machine, and are automatically advanced toward the right-hand or discharge end of the machine as the machine operates, the various operations being performed upon the tobacco leaves during their progress from the supply to the discharge end. To this end, leaf-advancing mechanism now to be described are preferably employed.

Leaf supply belts

At the left are three sets of parallel leaf-supply belts, each set comprising endless belts of frictional material, as for instance the belts 6 and 7 (Fig. 3), each of these belts being of soft rubber, and round in cross-section. Each set of belts passes over grooved pulleys 8 and 9, and the upper run of the belts slides on the surface of the table 1. The sets of belts 6 and 7 are laterally spaced apart so as well to support the blades of the leaves above the surface of the table, with the view, as far as possible, to avoid the leaves being dragged askew as they are advanced by these belts to the leaf-separating and advancing mechanism hereinafter described. The numeral 10 indicates a shaft to which each of the pulleys 8 is fixed, the shaft 10 having a sprocket wheel 11 driven by chain 12 coming from sprocket wheel 13 on a transverse shaft 14 journaled in the frame beneath the table 1, the pulleys 9 being loosely journaled on the shaft 14.

Supplemental leaf-advancing belts

Fixed to rotate with the shaft 14 are three pulleys 15 (Fig. 3). Over each pulley 15 passes an endless, supplementary leaf-advancing belt, there being three such belts, 16, 17, and 18, one for each pulley 15. The belts 16, 17 and 18 extend in advance of the supply belts 6 and 7 and to the right-hand end of the machine (Fig. 4) where they pass around a drum or elongated pulley 19 suitably rotatively supported in the adjustable, bearing brackets 20. In the present embodiment each of the belts 16, 17 and 18 is a flat leather belt, and the upper runs of the belts 17 and 18 slide along the upper surface of the table, whereas the table has an opening beneath a part of the upper run of the belt 16 for accommodating a lower series of leaf-advancing grippers hereinafter described. The supplementary leaf-advancing belts 16, 17 and 18 are driven by rotation of the shaft 14, as will be understood.

Leaf-separating and advancing mechanism

Adjacent the leaf-advancing belt 16, on the side of the latter adjacent the housing 4, is a relatively short belt 21 (Figs. 3 and 7), which passes over pulley 22 fixed to rotate with the

shaft 14, and also over a pulley 23, the latter pulley being rotatively supported in a bracket bearing 24 bolted to the frame, the upper run of the belt 21 also sliding on the surface of the table 1. Cooperating with the upper run of the auxiliary belt 21, so as to form a leaf-separating and advancing mechanism, or device, is a device which, in the present embodiment, includes a set of two parallel, endless belts 25 and 26 (Figs. 1, 5, 6 and 7), which are driven at greater speed than the belt 21. The belts 25 and 26 are of frictional material, as soft rubber, and cooperate yieldingly to press the leaves against a belt of lesser friction, as the flat leather belt 21. The gripping and separating belts 25 and 26 are preferably round in cross-section and pass over a relatively large grooved pulley 27 and a smaller grooved pulley 28, which pulleys are respectively journaled in the ends of a rocker, or rockable rigid plates 29, which plate is journaled, for relative rocking movement transversely of the leaves, on a transverse, rotatable shaft 30 lying in a plane above the table and hereinafter more specifically referred to, the pulleys 27 and 28 being at either side of the rocking axis.

Rotating with the driving shaft 30 is a grooved belt pulley 31 which is engaged by the upper runs of the belts 25 and 26 and which frictionally drives these belts, proper tension being given the belts 25 and 26 by a grooved belt-engaging pulley 32 adjustable in a slot 33 in the plate 29. The leaves on the supply belts 6 and 7 advance toward that end of the separating belts 25 and 26 supported by the larger pulley 27 and the proximate ends of the belts 6 and 7 overlap the plane of operation of the separating belts so as surely to deliver the leaves to the separating mechanism (see Fig. 7). The leaf-separating belts 25 and 26 operate in a vertical plane to one side of the supply belts 7 and 6, (Fig. 1), being generally in line with the butt or thicker portions of the leaves to be operated upon (see Fig. 1).

Pneumatic leaf-advancing mechanism

As the tobacco leaves approach the separating belts 21 and 25 and 26, it has been found desirable, in practice, to accelerate their advancing movement and to assist in preliminarily separating the leaves from each other for continued or further separation of the leaves by the leaf-separating and advancing device. To this end a pneumatic leaf-advancing mechanism is provided, which consists of air discharge conduits 34, one or more (Figs. 1, 5, 6 and 23), communicating with the end of an air supply conduit 35, which latter receives compressed air from a suitable source through the pipe 36, discharge of air through the conduits 34 being regulated by hand controlled valves 37. The conduits 34 may be made of flexible, pliable

metal, so that the discharge ends, or nozzles, of the conduits 34 may be bent and adjusted into different positions relative to each other and to the leaf-supply belts and the leaf-separating and advancing mechanism. As illustrated in Fig. 5, for instance, the nozzles discharge jets of air one in advance of the other and adjacent the butts of the leaves for acting upon the leaves and hastening their advance toward the leaf-separating and advancing mechanism.

Leaf-holding and advancing mechanism

From the leaf-separating and advancing belts, the leaves pass advance to a leaf-holding and advancing mechanism, which holds the leaf while a portion of the blade is stripped, or parted, from the butt end of the stem, the stripping operation at this stage being commonly called "butting". In the present embodiment, this leaf-holding and advancing mechanism includes two series of leaf-advancing grippers between which the leaf is gripped so as to be held during the butting operation. This mechanism includes an upper, endless series of traveling, soft, gripper pads, as soft rubber blocks or pads 38 (Figs. 1, 3, 4, 8, 9, 10, 29, 38, 39 and 42) held in recesses of metal members 39, each member 39 being supported on a link of an endless sprocket chain 40 passing around sprocket wheels 41 and 42, the sprocket wheels being mounted on a metal plate, or frame-piece, 43, pivotally movable on shaft 30, which frame-piece may be secured in stationary position for operation alongside and in front of the stripping members, hereinafter described, by being bolted to the front of the housing 4 as by the three bolts 44. The axis of the sprocket wheel 42 is journaled in a bracket 45 having a slot 46 entered by bolts 47, the end of the bracket 45 being adapted to abut the end of screw 48 which may be locked in adjusted position by the nut 49. After the adjustment is made, it may be fixed by screwing up the bolts 47. The plate or frame 43 is provided with a channel 50 (Figs. 10 and 42,) in which runs the chain 40, and the links of the chain have anti-friction, or roller bearings 51, engaging a projecting portion or track 52 in the channel 50, so as to permit advancing movement of the chain 40 with but little friction. The lower run of the upper series of soft rubber gripper blocks 38 is adapted to contact with the flat, supplementary leaf-advancing and supporting belt 16 so that the tobacco leaves will be gripped and advanced by the movement of these blocks and belt. As illustrated, the path of the upper series of grippers 38 overlaps the leaf-separating and advancing belts 25 and 26, and the lower run of the series of pads 38 upwardly inclines from the central portion so as initially gradually to take hold of the advancing leaves and similarly relinquish grip

thereof. The lower run of the series of gripper blocks 38 is yieldingly pressed toward the flat leather belt 16 by presser bar 53 (Figs. 8 and 42) playing up and down in a recess 500 in frame 43, and with which the roller bearings 51 may contact, the bar 53 being stressed downwardly by a number of helical springs 54 engaging recesses in the block 53 and the frame 43.

The sprocket wheel 41 which drives the upper series of gripper blocks 38 rotates with shaft 30 hereinbefore referred to. By removing the bolts 44, the frame 43 together with the gripper blocks 38 and their supporting chain, etc., may be vertically rotated on the shaft 30, so as to expose the mechanism lying toward the housing 4; in the present embodiment to expose certain leaf-stripper elements of the butting mechanism, as will hereinafter appear (see Fig. 33).

Directly beneath the supplementary leaf-advancing belt 16 and opposite the field of operation of the lower run of the series of gripper blocks 38, the table 1 is cut away in order that a lower series of supporting gripper blocks may coact to cause the tobacco leaves to be firmly gripped between the belt 16 and the upper series of gripper blocks. In some instances this lower series of gripper blocks may be similar in character and mounting to the upper series just described, but in practice it is found that better leaf-holding and advancing results follow when the lower grippers consist of a series of hard-wood blocks in contradistinction to the soft rubber pads of the upper series.

Referring to Figs. 9, 10, 29, 39, the hard-wood gripper, or presser blocks of the lower series are indicated by the numeral 60. Like the blocks 38, the blocks 60 are carried by links of a lower sprocket chain 601, and have roller bearings 602 (Fig. 29), the sprocket chain engaging sprocket wheels 603, 604, the latter of which is journaled in bracket bearing 605, secured to the frame by bolts 606, passing through a slot in the bracket 605, and adjustable by loosening bolts 606. At 607 is an adjustably positioned stop pin, for controlling position of bracket 605. Rigidly supporting the upper run of blocks 60 is a stationary shoe 608, on which the rollers 602 travel, this shoe maintaining the upper run of blocks 60 in contact with the belt 16. For driving the sprocket chain of the lower series of gripper blocks, sprocket wheel 603 is carried by and rotates with a transverse shaft 55, beneath the table, shaft 55 being driven from shaft 30 by intermeshing spur gears 56 and 57 (Fig. 2).

Leaf-stripping mechanism

One of the most important features of the invention relates to the construction of the devices which participate in directly effecting removal of the blade and veins of the leaf

from the stem thereof; also to the relative movement, on the one hand positively effected and on the other hand permitted, between such devices and the leaf to be stripped. In 5 the present embodiment the stripping mechanism includes a plurality of closely associated leaf strippers having advancing movement in the stripping field, the associated strippers providing one or more gangs of strippers, the strippers of a gang being movable in a recurrent path and on and off the leaves transversely of the plane of the leaves. In the present embodiment two such gangs are employed, but it is to be understood that 10 under some conditions one gang or three or more gangs may be employed without departing from the broader aspects of the invention.

In the present embodiment the leaf-stripping device includes a member, as the relatively thin, steel blade 80 (see Figs. 33, 35, 36) having a stripper edge 81. As illustrated the stripper edge 81 opens into and proceeds from the lower end or edge of the blade in a 25 sinuous or corrugated line returning in a counterpart, opposite stripper edge 82 to the end of the blade, the blade being thus in the nature of a fork in which the parts 83 and 84 are the tines, a stem-receiving stripping aperture 85 being thus formed. In practice, 30 it is preferred that the aperture 85 should have a general flare outwardly from its inner end 86 to the outer end 87 of the blade. The sinuous stripping edge is preferably 35 given clearance in the proper direction. By reason of the sinuous or corrugated edge, jamming of the stem and leaf in the blade is minimized, if not altogether prevented, and it is found that this stripper breaks down 40 and starts parting the veins of the leaf so that they are more readily stripped from the stems. This breaking-down and preliminary partial parting is especially desirable when the stripping is very quickly effected, as 45 for instance in the stemming operation in which the stems are quickly stripped from the greater portion of the length of the blades of the leaves. Both the butting mechanism and the stemming mechanism include stripping members, as above described. Also, in 50 each of the butting mechanism and the stemming mechanism the provisions for supporting and permitting movement of the stripping blade are similar, so that a description of one will suffice for all.

Referring now more particularly to Figs. 13 to 21 inclusive, each stripping blade 80 is fixed to a relatively stiff and heavy haft 88 from the lower end of which latter it downwardly projects. The haft 88 has a vertical slot 89 and a track follower, or head 90, which latter may be provided by a crook or bend in the haft, as illustrated. The numeral 91 indicates one of a movable series or gangs of carriers or carrier blocks each having haft

guides, or channels 520, and an upstanding, angular extension or bracket 92, in which is a guide opening or aperture 93 in which vertically slides a hollow control pin 94 having a rounded head, or rail follower 95. Between the pin 94 and the haft 88 in each stripper is a helical spring 96 which lies partially inside the hollow pin, the lower end of the spring lying against the haft or its follower 90, there being a guide pin 97 upwardly projecting from the follower 90 and into the pin 97. Numeral 501 indicates a stop consisting of a pin engaging in the slot 89 of the carrier block and threaded into such block to limit sliding movement of the blade 80. Each carrier block 91 has an inward, horizontal extension 98 (Fig. 21) which forms a link of a sprocket chain 99, by means of which chain the individual carrier blocks are loosely connected or articulated in endless series, the 80 butting mechanism and the stemming mechanism each including a series of stripping blades 80, separately movable on its carrier block 91, as above described.

Butting mechanism

In the present embodiment, the stripper blades of the butting mechanism have an advancing movement with the leaves and also a movement longitudinally of the stems toward the butt ends of the stems. In addition they have approaching and receding movements, separately one of another, relative to and transversely of the stems of the leaves, and the advancing and longitudinal movements just mentioned are simultaneously effected. In the form illustrated, sprocket chain 99, to which the butting strippers are connected as before explained, is supported on sprocket wheels 100 and 101, said sprocket wheels being so disposed relative to each other that the front series of butting stripper blades 80, in the operation of butting, move in a path diverging, or inclining, rearwardly from that of the advance movement of the leaves as gripped between the leaf-holding gripper blocks 38 and the belt 16, the divergent path being mainly in horizontal plane and in the direction of general advance of the leaves, as illustrated for instance in Fig. 12. The butting stripper blades, as they move in their divergent path, also move longitudinally at the same speed as the gripper blocks 38, so that there is substantially no forward or back bending of the stems. For driving the chain 99 of the butting mechanism, the sprocket wheel 100 is fast to a depending shaft 102 (Fig. 11) bearing in a sleeve 103, which latter is a depending portion of the framework of the housing 4, the upper end of the shaft 102 having a worm gear 104 (Fig. 20) rotated by a worm wheel 105, which latter in turn rotates with a long, horizontal shaft 106 supported in bearings at the rear of the housing 4, the worm wheel 120

106 being covered by a removable cap 107 (Fig. 2).

Supported on the casing 4 are rails and tracks which cooperate positively to raise and lower the butting stripper blades depending therefrom and as they move in their endless path. Referring to Figs. 13, 16 and 20, it will be seen that the housing 4 has an upper chamber 108 and depending frame pieces or webs, one of which latter, for instance, is indicated by the numeral 109 (Fig. 13). Supported by the web 109 are stripper supporting tracks and devices, as rails, which participate in guiding and effecting certain movements of the stripper blades. As illustrated in Fig. 13, there is an upper, generally horizontal, track section, one part of which is indicated at 110 and another part at 111, this track extending continuously along the rear of the web 109, as indicated by the dotted lines 112. For the sake of clearness of illustration, only two butting stripper blades and their carriers are illustrated in Fig. 13. It is to be understood, however, that each carrier block 91 has a stripper blade associated therewith, as before explained, thus providing an endless series, or gang, of butting stripper blades close alongside each other, as for instance more clearly seen in Fig. 33. The followers 90 of the shafts 88 of the stripper blades proceed on the rear track portion 112 from track portion 111 to track portion 110, these track portions curving around the web 109, and the track portion 110 terminating in front, as for instance at 113. When the followers 90 reach the point 113, they drop onto a lower front horizontal track section 114, so as to bring the butting stripper blade quite close to the leaf to be butted. Thereupon, the follower gradually descends a front inclined track portion 115 fully to rest on and be supported by the leaf to be butted. During the butting operation the track follower 90 overlaps a horizontal front track portion 116 which inclines rearwardly of the machine and in the divergent direction before mentioned, this track portion 116 serving where needed to limit the extent of descent of the butting, stripper blades. Toward the right-hand end of the front divergent path the butting stripper blades are gradually lifted from the leaves by the inclined, or rising, track portion 117, whence they proceed onto the elevated rear track portion 111 and thence in their recurrent path around the web 109 for subsequent engagement with the leaves.

Above the front track portions of the butting mechanism is a device which cooperates to stress the springs 96 of the respective strippers in the stripping operation, and also to urge the strippers from the track section 110 into contact with the leaves. In the present embodiment this cooperative device 65 consists of a stationary rail, or abutment, the

initial incline 118 of which acts through the pin 94 and the spring 96 resiliently to thrust the respective butting stripper blades downwardly, the intermediate horizontal portion 119 cooperating through springs 96 resiliently to keep the stripper blades down, but permitting their rise and fall, and cooperating to permit relief movement of the strippers transversely of the stems of the leaves. The rising rail portion 120 similarly resiliently maintains some downward thrust on the butting stripper blades but permits gradual rise of these blades off the leaves by expansion of springs 96, at the end of the front advancing and divergent path of the butting blades. It will be understood that suitable devices may be employed for steadyng and guiding the carrier blocks in a vertical plane as they move in their recurrent path. One of such devices is shown in Fig. 2, wherein the numeral 121 indicates a strap or guide bolted to the main frame at 122 and to a bracket 123. The leaf material stripped from the stems by the butting operation may conveniently be confined and discharged from the machine 90 by chute 124.

Leaf-stemming mechanism

The stemming mechanism includes an endless series, or gang, of loosely articulated stripper carriers, each carrier having its relatively slidably stripper with flaring stem-receiving aperture, as heretofore explained, in connection with the butting feature of the stripping operation. Referring to Figs. 1 and 33, the general location of the gang of stemming strippers is indicated by the numerals 125, being in advance of the butting mechanism. As in the butting mechanism, the stemming strippers also move in a recurrent path and from a rear track section 126 to a front track section 127 (Fig. 15). Similarly, a spring-stressing device, as the abutment or rail 128, overlies the front track section 127, and has inclines at each end, the incline at one end being at 129 in Fig. 15. In the present embodiment, however, the path of advance of the stemming strippers is preferably parallel to that of the leaves, as advanced by the supplemental belts 16, 17 and 18, the front track section 127 continuing along this parallel path, and thus being at an angle to that of the rearwardly inclined, front track section 116, over which the followers of the butting strippers pass. The carriers, or carrier blocks, of the stemming strippers are embodied as links of a sprocket chain, as explained for those of the butting mechanism. This chain for the stemming strippers is indicated by the numerals 129 (Figs. 11, 12 and 18) being supported on sprocket wheels 130 and 131, the latter of which rotates the vertical shaft 132, bearing in the sleeve 133 depending from housing 4. For adjusting the tension of the sprocket 130

chain 129, the shaft 134 supporting the same, rotates in a bearing 135 which may be held in different adjusted positions relative to the bearing 133 by means of the set screw 136, and which may be adjusted relative to the bearing 133 by moving the adjusting pin 137 in one or the other direction by rotating the nut 138. On the upper end of the shaft 132 is a worm gear wheel 139 in mesh with a worm 140, which latter rotates with a short horizontal shaft 141 supported on bearing pieces inside the housing, the shaft 141 having a spur gear 142 meshing with the spur gear 143 rotating with the long horizontal shaft 106, the shaft 106, at this end of the machine, being supported in bearings 144 over which lies a removable cap 146 and also in the bearing 147 at the end of the housing. Thus, by rotating the shaft 106, advancing movement of the stemming strippers and of the butting strippers and in their recurrent paths alongside their respective tracks, is effected.

Adjustable track sections

The numerals 150, 151, 152 and 153 indicate a plurality of succeeding track sections, pivoted to each other at the points 154, 155 and 156, the track section 150 having a stationary pivot 157. The pivoted track sections are adjustable to different elevations and different angular relations to each other, so as positively to elevate strippers passing thereby. The pivoted track section 153 preferably has a beveled leading end 158 so as to lie on an incline 159 in different adjusted positions of the pivoted track sections, the upper surface of the beveled section 158 being substantially flush with the portion of the track on which it lies. To respective of the pivots 154, 155 and 156 are connected links 160, 161, 162, these links being also pivoted to respective arms 163 of respective transverse shafts 164, the shafts 164 being rotatably mounted in the housing 4. Fixed to each shaft 164 is a crank 165 having an aperture in its outer end through which loosely passes a screw threaded pin 166, the inner end of each pin 166 being engaged by nut 167 lying in a channel 168, which latter prevents rotation of the nut 167. By rotating a pin 166 in one direction, the clamping effect of the nut may be relieved so as to permit the crank 165 to be adjustably moved along the slots 169, for raising or lowering the links 160, 161 and 162, and thus adjusting the pivoted track sections relatively to each other and to the main front track section of which they are continuations. In this wise it will be perceived that, by adjusting the pivoted track sections, the strippers passing therealong may be caused positively to rise at various points in their path of movement, and that the order of the occurrence of this positive rising movement of the strippers is adjustably variable at will.

Notwithstanding this positive rise, further rise with resilient restraint is possible by reason of the incline of the rail.

In their advancing paths, both in conjunction with the butting operation and the stripping operation, the leaves to be stripped are supported from below and close to the path of movement of the stripper blades. In the butting mechanism, this leaf-supporting means comprises two leaf-supporting devices spaced longitudinally of the stem, each device including two parallel, steel ledger blades 170 and 171 for the butting strippers (Fig. 37) and two similar parallel ledger blades 172 and 173 for the stemming strippers (Fig. 16). In each device the set of ledger blades is adapted to receive the stripper blade closely therebetween, one being close to the rear and the other being close to the front of the stripper blades, so that downward bending of the stems between a set of ledger blades is practically entirely prevented. As the leaves advance with the butting mechanism, their butt ends are trimmed off by a fixed knife 174 which may be in line with one of the ledger blades. This knife may be a circular sharp disk in the diverging path of the leaves to be butted and fixed in position by a screw 561, in a supporting plate 562 adjustably bolted to the machine frame by bolts 563 passing through slots in plate 562.

Leaf-centering device

The leaf-centering device cooperates either to accelerate the advance movement of the leaves or to decelerate the advance movement thereof, so as in either instance to assist proper positioning of the stems of the leaves in the stripping apertures of the respective strippers. In the present embodiment, the leaf-centering device includes a leaf-centering roll 175 (Figs. 2, 4, 18 and 40), alongside the advancing path of the stripper apertures, this roll being rotated in leaf-advancing direction at a peripheral speed greater than that of advance of the strippers. As viewed in Fig. 18, it will be seen that the periphery of the roll 175 overlaps the stem-engaging position of the apertures of those strippers which are adjacent the roll. In case it is found that efficient leaf-centering is not effected by the use of one leaf-centering roll, two or more may be utilized, one in advance of the other, as illustrated, and each overlapping stem-engaging position of the stripper apertures. For rotating the leaf-centering rolls 175 they are provided with sprocket wheels 176 engaged by a chain 177 driven by a sprocket wheel 178 rotating with the shaft 179, the shaft 179 extending transversely beneath the table 1 and being rotated by a sprocket chain 180 in turn driven by a sprocket wheel 181 on a shaft 55. The leaves to be stripped ride on the periphery of the leaf-centering roll,

the roll being knurled or otherwise roughened to develop considerable leaf-impelling effect. When the leaf stem contacts the approach side of the centering roll, the latter tends, by its greater speed, to wipe the stem upwardly and forwardly into the aperture in the stripping blade. The knurled surface assists by giving somewhat positive leaf-impelling effect. Thus should the tine of the approach side of the stripper be resting on the stem, the latter will tend to be swept forwardly and into the aperture. As the other tine of a stripper leaves the leaf-centering roll, the immediately adjacent peripheral portion of the latter is moving forwardly and downwardly. The speed of advance movement on the delivery side of the roll relative to that of the strippers is not so great as on the approach side, and this slowing of relative speed tends to impel or divert a leaf stem at that point into the aperture in the stripper. If satisfactory operation is not attained with one leaf-centering roll, two or more may be used. In the embodiment illustrated the leaf-centering roll has an annular, central channel 525 in which the ends of the strippers are received as the machine operates.

Stem-drawing mechanism

In the present embodiment the stem-drawing mechanism includes a pair of stem-drawing rolls 182 and 183 (Figs. 18, 20 and 22) disposed alongside the paths of the strippers to receive and mutually cooperate to grip the advancing leaf stems. These rolls are angularly movable relative to each other transversely of the stems, the upper roll 182 being pivoted or hinged for such angular movement in a plane longitudinally of the axes of the rolls. Any practical manner of pivoting these rolls for the angular movement is within the purview of this invention, but it is preferred to journal the upper roll 182 in the arms of a yoke 184 pivoted on a frame bracket 185, the roll 182 having a spur gear 186 in loose mesh with a spur gear 187 on the lower stemming roll 183, the gear 187 meshing with the relatively large spur gear 188 driven by a gear 189 on the main driving shaft 190 of the machine. As the amount of angular movement of the yoke 120 may be relatively small, the loose meshing of the gears 186 and 187 permits such angular movement while maintaining mesh therebetween.

Means are provided for insuring stem-gripping pressure between the drawing rolls in their different relative positions to each other. Sufficient weighting of the upper roll would answer the purpose, but more efficient results and better control follows when the rolls are resiliently pressed toward each other to grip the stems. To this end a resiliently acting device is employed consisting of an upstanding rod 191 which

emerges from the top of the housing 4 and is downwardly pressed by a spring 192 (Fig. 24). On the rod 191 is a collar 193 with which a rotative cam arm 194 cooperates to lift the rod 191 and thereby relieve the stemming rolls of gripping pressure, the cam 194 being pivoted on top of the frame 4. Upstanding from the frame 4 is a hood 195 enclosing the spring 192 and supporting an adjustable screw-threaded sleeve 196 for regulating the tension of the spring 192. The lower end of the rod 191 rests upon the free end of the top of the yoke 184. For limiting the extent of separating movement between the drawing rolls, a stop 197 is provided (Fig. 18). As illustrated, this stop may consist of a pin threaded to the housing and adjustable up and down to different positions in the path of the yoke 184. The advance ends of the rolls are, one generally cylindrical, indicated at 198, and the other conical as at 199, the ends also each having a stem-advancing helix, or screw-threaded portion, for positively advancing the stems of the leaves. The gripping surfaces of the stemming rolls are preferably cylindrical in greater part, and of elastic, frictional material, as a quality of rubber or rubber compound having considerable density. The plane of mutual gripping between the stemming rolls is in the horizontal plane of the ledger blades with which the stemming strippers cooperate. By the construction described it will be noted that the stemming strippers and the rolls are automatically shiftable relative to each other so as to confine the drawing strain on the stem to a tensile strain substantially free of strain transversely of the plane of mutual cooperation of the drawing rolls. The stemming rolls are disposed at the rear side of the path of the stemming strippers, whereas it will be noted that the leaf-advancing and holding device is disposed in front of the path of the butting strippers.

Severing the separated leaf stems

Turning to Figs. 4, 14, 26, 27 and 28, the numeral 200 indicates a stem-severing knife, or cutting disk, reciprocally adjustable alongside the advancing path of the stemming strippers. The disk 200 is carried by a pin 201 on a reciprocal carriage 202, having a rack, or gear teeth, 203. For adjusting the carriage 202, the teeth 203 are engaged by a spur gear 204 fixed to rotate with a transverse shaft 205, this shaft being below the surface of the table 1 and projecting through and supported in a bracket (Fig. 26), depending from the table near the front of the machine. Also rotating with shaft 205 is a worm wheel 206 meshing with a worm 207 on the vertical shaft 208, having an operating handle 209. The numeral 210 indicates a scale plate at the front of the machine. Re-

ciprocally movable over the gauge plate is a pointer 211, mounted on a slide 212, which slide has rack teeth 213 in mesh with the spur gear 214, rotatable with shaft 205. By 5 rotating the shaft 208 in one direction or the other, the cutting disk 200 may be advanced or retracted longitudinally of the path of the strippers, and its position determined by the scale 210. In the present embodiment 10 the knife 200 is disposed in front of the stem-drawing rolls, so that the stems being drawn are advanced by the strippers into severing contact with the cutting disk 200.

15 *Leaf-loosening or aperture-clearing mechanism*

Turning to Figs. 1, 15, and 16, the numeral 215 indicates a device alongside the path of the strippers, and which cooperates 20 to press the leaves downwardly and in the direction of the open end of the apertures in the stripping blades. In the present embodiment, this device includes a relatively long, aperture-clearing blade, also indicated 25 by the numeral 215, which lies in overlapping relation to a plurality of the stripper blades, and is loosely, pivotally mounted, at 216, preferably by means of ball bearings, on a bracket or housing frame piece 217, the pivotal point being above the plane of advance 30 of the leaves. The numeral 218 indicates a weight adjustable on an arm 219 of the blade and adapted to regulate and to counter-balance the said blade as desired. The lower 35 clearing edge of the blade, at its opposite ends, inclines away from the plane of the leaves, as indicated at 219 and 220. The lower portion of the blade 215 lies relatively close to the strippers. In the present embodiment, however, the upper portion 221 of said blade inclines upwardly and forwardly from the stripper blades, a relatively wide space being provided between the portion 221 and the plane of the leaves on the table, so 40 that the leaf material being stripped from the stems in the stemming operation has an opportunity to be deflected forwardly during the stemming operation instead of assuming a compact mass of leaf material jammed 45 against the strippers. In the present embodiment the aperture-clearing blade has a lug 560 (Fig. 15) for contacting stationary pin 561 which limits the extent of upward movement of the clearing blade. Pin 561 is 50 adjustable for varying said limit.

Stem-weakening or gashing mechanism

The stems of the leaves may be weakened, as by being broken, or partially severed or gashed, before the stems are separated from the blades of the leaves, to the end that in the stemming operation the greater part of the length of the stem will assuredly be separated from the remainder and without injuring the leaf blade adjacent that part

of the stem which may remain as a part of the useful leaf blade material.

Turning to Figs. 1, 30 and 31, the numeral 222 indicates the stem-weakenener, being in the present instance a rotatable cutting disk, the edges of which are quite sharp so as readily to sever some of the fibers of the stems of the leaves. When such a cutter is employed, it faces the blade of the leaf and is spaced from the table, or other leaf support, so as not completely to sever the stems, but rather to gash the same. In order that the particular point of weakening, or gashing, the stem may be selected, the cutter 222 is mounted for being shifted lengthwise of the leaf. To this end the rigid member, or frame piece, as the angular blade 223, extends over the path of the advancing leaves, and is suitably secured in stationary position for operation, as for instance by being fastened 70 to the supporting piece 43 which carries the upper series of leaf-gripping and advancing block 38. Projecting from the front face of the blade 223 are upper and lower flanged guide plates 224 and 225, between which is a slot 226. The numeral 227 indicates a lever fulcrumed on a bracket 228, and in the lower arm of this lever is journaled the shaft or axle 229 of the cutting disk. The lever-supporting bracket 228 is slidable along the angular plate 223, and is held in any of several adjusted positions by a bolt 230, which passes through the bracket 228 and engages a nut 231 in the slot 226. By screwing up the bolt 230, the lever-supporting bracket 80 may be clamped to the frame piece 223. The numeral 232 indicates the pivot of the lever 227. Said lever has an upstanding arm 233 in front of the members 224 and 225. Threaded in the arm 233 is a screw 234, the inner end of which contacts with the member 225. The lever 227 also has another arm, or shoulder, 235, which is upwardly presented, and is engaged by an adjusting screw 236 passing vertically through bracket 228. By 85 loosening the bolt 230, the lever 227 may be adjusted on the frame piece 223 lengthwise of the leaves to any position. By manipulating the adjusting screws 236 and 234, the lever may be adjustably rotated on its fulcrum so as to dispose the disk 222 at different distances from the table 1. When the cutting disk is employed, its edge should 90 preferably be out of contact with the table, or other support for the leaves, so as not to cut the blades of the leaves, but to cut only the stems. For rotating the cutting disk 222, is axle 229 is provided with a sprocket wheel 237 engaged by a chain 238, which latter also 95 engages a small sprocket wheel 239 on a shaft 240, journaled in the frame piece 223 and having a relatively large sprocket wheel 241 driven by a chain 242 from sprocket wheel 243 rotating with the shaft 30 which 100 drives the upper series of gripper blocks 38. 105

115

120

125

130

In addition to the cutting or weakening function of the gashing disk 222, it will be noted that this disk cooperates with the butting cutter 174 to predetermine a length of stem which is subsequently to be drawn in the stemming operation, one of these cutters acting on the stem at one point in its length, and the other at a different point in its length. It will furthermore be noted that the stemming cutter 200 will act to sever the drawn stems at practically a predetermined point, in the event that the gashing disk does not weaken the stem sufficiently to assure parting of all drawn stems before reaching the stem-cutting disk 200.

General driving and operating mechanism

At 244 is a driving belt pulley fixed to the main driving shaft 190, and adapted to be driven by a belt (not shown) from a suitable source of power, a belt shifter being indicated at 245 and an idler belt pulley at 246. The long driving shaft 106 is driven from shaft 190 through sprocket chain 247 engaging sprocket wheels 248 and 249 on shafts 106 and 190. On shaft 106 is a worm 250 (Fig. 2) engaging a worm gear 253 on a short, transverse shaft 254, suitable bearings being provided for supporting the shaft 254 on the housing 4. On the shaft 254 is a sprocket wheel 255 engaged by sprocket chain 256, the chain also engaging a sprocket wheel 257 for rotating the shaft 30. Shaft 55 is driven from shaft 30 through the intermeshing gears 56 and 57, and on the rear end of shaft 55 is sprocket wheel 258 which drives sprocket wheel 259 through chain 260, rotation of sprocket wheel 259 effecting rotation of the shaft 14 and the shaft 10.

The numeral 261 indicates a chute for guiding and discharging the stems drawn by the stemming mechanism.

Operation in general

In operation, the operator places the unbutted and unstemmed leaves upon the series of supply belts 6, 7, with the butt ends of the leaves against the butting plate 5 for aligning the butts. These leaves are largely elevated above the table by the belts 6, 7, so that, as they are advanced by the supply belts, they tend to maintain their position as placed on these belts instead of being drawn askew by dragging contact with the upper surface of the table. The supply belts advance the leaves to within the sphere of operation of the leaf-separating and advancing belts 26, this advance movement being supplemented and accelerated by air blast through the air conduits 34. The air blasts tend not only to accelerate the leaves, but also to separate leaves which may be in close juxtaposition to each other, or in superposed relation to each other. The round leaf-advancing belts 26 and 27 are driven at higher speed than the

co-acting, flat, auxiliary, or supplemental, belt 21, so that leaves which are relatively close together before entering the leaf-separating mechanism are more widely spaced from each other by the quicker advance movement imparted thereto at the leading end of the separating mechanism. These more widely separated leaves are thereby in better relation for being individually received in the stripping apertures of the butting strippers. At the leading end of the gang of butting strippers, these strippers pass in a circular path from the front to the rear track and they then diverge rearwardly and move in a path rearwardly inclined to that of general advance of the leaves. At a point in their path, the plane of the aperture of the butting stripper lies at right angles to the length of the leaves, so that the lower end of the aperture is presented, in its widest extent, to the stem of the leaf. However, as the butting strippers move in their divergent path, the plane of the stripping aperture will assume a position diagonal to the length of the stems, that is to say, it will, in effect, have rotated in the plane of the leaf and relative to the leaf, so that the opposite stripping edges of the aperture will lie in respectively different planes transversely of the stems. The movement of the strippers in their inclined path includes a stripping movement longitudinally of the stems toward the butt end of the stems, and this stripping movement removes leaf blade material from the stems, with resultant butting of the leaves. It will be seen that during the stripping movement in its inclined path, the plane of the aperture of the stripper will be diagonally or obliquely presented to the length of the stem so as, in effect, to offer a relatively narrow aperture as compared to the same aperture when at right angles to the length of the stems. Thus, should a relatively slender stem be in the aperture when the latter is at right angles thereto, the diagonal relation of the aperture will bring the edges of the aperture closer to the slender stem, with consequent more positive stripping effect. The leaf-advancing and holding grippers 38 and 60, and the intervening supplemental belt 16, are driven at the same speed as the advancing component of the butting strippers in their inclined path, so that there is practically no tendency for bending or breaking the stems of the leaves, as by a forward or backward movement between the leaf-advancing grippers and the stripper blades. On the contrary, the stripper blades advance with the stems as advanced by the grippers 38.

During their stripping movement, the butting stripper blades may also move independently of each other, and upwardly, transversely of the stems. The stripper blades lie on the stems or leaves so as to be adapted to yield to upward thrust engen-

dered by leaf material, such yielding movement being permitted by the provision of the springs 96, one for each stripper. Furthermore, the rail 119 cooperates to stress the springs 96 so as to impart resilient, downward pressure of the strippers on the leaves being stripped. Hence, in case the stripping movement of the butting strippers lengthwise of the stems should be opposed by the leaves, as for instance by the jamming or opposing effect of an accumulation of leaf material in the apertures of the stripper blades, or against these blades, relief movement or jam-relieving movement, at an angle to that of the normal stripping movement between the edges of the apertures and stems, is provided for, the edges of the apertures being at the same time resiliently restrained against stem-disengaging movement. In the present embodiment, it will be seen that the stripping apertures widen toward their open ends, so that the rise of the strippers tends to dispose a wider portion of the aperture relative to the intercepting stem.

Referring to Fig. 32, it will be seen that the opposite stripping edges of the stripper aperture have portions at different distances from each other at different distances from the end of the stripper, the aperture-edges being of generally smoothly corrugated contour, with opposite rounded crests 262 and 263. For certain types of tobacco, it may be desirable to employ more crests or corrugations, as for instance illustrated in Figs. 13 or 36. As the butting strippers move in their endless, or recurrent, path, they are positively lifted from the plane of the stems at the completion of the butting operation and are then carried on the rear track 117, whence eventually they are carried over the path of the leaves and descend onto the leaves, as previously explained. During the butting operation, the blades and adjacent stems of the leaves are relatively softly gripped and held by the grippers of the leaf-holding and advancing device, so as not to be injured.

Preliminary to the stem-drawing operation, the stem-weakening cutter 222 may be disposed to gash the stems adjacent the tips of the leaves, as before explained.

The stem-holding and drawing grippers carry the butted leaves to within the sphere of operation of the stemming strippers, as will now be understood, and the leaf-accelerating roll, or rollers, 175 cooperate to center the butted ends of the stems in the apertures of the stemming strippers, preliminary to the stem-drawing operation. For guiding the stems into cooperative relation to the drawing rolls 182 and 183, the curved guide 264 is provided (Fig. 18), being a flat plate carried by an arm of the yoke 184 and spaced from and above the lower drawing roll 183, opposite the cylindrical, helical portion of

the latter roll. The pitch of the helices of the drawing rolls is such as to advance the butted stems at the same speed as that of the stemming strippers. The stems engage in the corrugations of the helices and are positively advanced to between the cylindrical, gripping surfaces of the drawing rolls.

During the stem-drawing operation, the leaves are drawn over the parallel ledger blades which, in the present embodiment, have no upward or downward movement, the edges of these ledger blades remaining in constant planes, which are substantially in the same horizontal plane as the gripping plane between the drawing rolls. The drawing strain will, therefore, be a tensile strain on the stem without substantial lateral strain. In the stem-drawing operation, the stripper blades have the relief, or jam-relieving, movements before explained in connection with the butting operation, and which need not be further explained. It is to be noted, however, in the stemming operation, that the upward relief movement of the strippers is a movement tending to free the leaf and stem from the stripping blade and not a movement laterally to strain the stem between the stripper blade and the edges of the stripping apertures. Thus, in the various positions in which a stem may lie in the stripping aperture, the drawing strain on the stem will be a tensile strain, substantially free of positive bending strain, either up or down. In this wise the breaking of stems during the drawing operation is greatly minimized.

It is found desirable, especially in connection with tobacco leaves of certain qualities, at times positively to effect the relief, or jam-relieving movement, hereinbefore referred to. It is within the purview of this invention to effect such positive relieving movement in connection either with the butting strippers or the stemming strippers. As herein illustrated, however, in conjunction with the stemming strippers, should there be an unusual obstruction to relative stripping movement between the leaves and the strippers, or if for any reason more efficient results are attained thereby, the pivoted track sections 150 et seq. may be adjusted to be engaged by the track followers 90 of the strippers, thereby positively to elevate the stripper blades at this or that point in their path of advance movement, the order of elevation being alterable, as before explained. This positive elevation may be regarded also as a safety or cautionary measure in conjunction with the stripping of any quality of leaves, and the provision thereof has a tendency to permit the stem-drawing operation to be performed at a somewhat lower speed than theretofore, with the consequent advantage of lessening of breakage of stems by the drawing operation.

During the relief movement hereinbefore referred to, and especially when positively accomplished as explained, the leaf-clearing blade 215 cooperates to urge the leaf material toward the wider portion of the stripping apertures in the stripping blades, thus tending to clear the blade material from clinging to the blades or to the edges of the apertures thereof, and to free the apertures of leaf material. As before explained, these stripper blades move in a recurrent or endless path. At the leading end of the gang of stemming strippers, the latter move to position over the butted stems and descend to position thereon, so that the stems will be engaged in the apertures, as will now be understood. When the stem-drawing operation has been completed, the stems are discharged at the rear of the machine, and the blade material stripped therefrom is carried by the supplemental leaf-advancing belts, out of the sphere of operation of the stemming strippers.

Fig. 34 is an enlarged view and diagrammatically illustrates a leaf in the butting operation and before the butting stripper has rotated to set itself askew to the axis of the stem. It will be observed that the beveling of the edges of this blade has widened the stripping aperture on the side opposite the accumulation of leaf material removed by the butting operation. Fig. 35 similarly illustrates beveling of the stripper blade for the stemming operation. As the relative movements between blade and leaf are the reverse of each other in these different operations, the beveling, or clearance, is in opposite directions respectively on the different blades.

Whereas the mechanism herein described is illustrative of the invention, it is to be understood that the invention may be embodied in mechanism differing in detail from that herein described without departing from the spirit of this invention. Detail constructions more or less differing from those herein described are included in applicant's prior applications Serial No. 246,462, filed January 13, 1928, Serial No. 256,397, filed February 23, 1928, Serial No. 259,448, filed March 6, 1928, and Serial No. 260,357, filed March 9, 1928, and it is to be understood that the present application is a continuation in part of said prior applications in respect to disclosure common to this application and any of said prior applications.

Having described my invention, what I claim as new and desire to secure by Letters Patent is:

1. In a machine of the character described, in combination, stripping mechanism, and means adapted to cause relative stripping movement between said mechanism and the leaves to be stripped, said stripping mecha-

nism including a gang of leaf strippers, strippers of which are mounted for relief movement transversely of the leaf-stems in the stripping operation, and have stem-receiving, stripping apertures, flaring in a direction opposite to that of said relief movement.

2. In a machine of the character described, in combination, stripping mechanism, and means adapted to cause relative stripping movement between said mechanism and the leaves to be stripped, said stripping mechanism including a gang of leaf strippers, strippers of which are mounted for relief movement transversely of the leaf-stems in the stripping operation, and have stem-receiving, stripping apertures, flaring in a direction opposite to that of said relief movement, and a device adapted yieldingly to restrain said relief movement of said strippers.

3. In a machine of the character described, in combination, stripping mechanism, and means adapted to cause relative stripping movement between said mechanism and the leaves to be stripped, said stripping mechanism including a gang of leaf strippers, strippers of which are mounted for relief movement transversely of the leaf-stems in the stripping operation, and have stem-receiving, stripping apertures, flaring in a direction opposite to that of said relief movement, a device adapted yieldingly to restrain said relief movement of said strippers, and a device adapted to restrain the extent of transverse movement of the stems under pressure of said strippers.

4. In a machine of the character described, in combination, stripping mechanism, and means adapted to cause relative stripping movement between said mechanism and the leaves to be stripped, said stripping mechanism including a gang of leaf strippers, strippers of which are mounted for relief movement transversely of the leaf-stems in the stripping operation, and have stem-receiving, stripping apertures, flaring in a direction opposite to that of said relief movement, a device adapted yieldingly to restrain said relief movement of said strippers, a device adapted to restrain the extent of transverse movement of the stems under pressure of said strippers, and means adapted to move said strippers in a recurrent path and on and off the leaves to be stripped.

5. In a machine of the character described, in combination, stripping mechanism and means adapted to cause relative stripping movement between said mechanism and the leaves to be stripped, said stripping mechanism including a gang of leaf strippers having stem-receiving, stripping apertures, the stripping edges of respective apertures lying in a plane diagonal to the length of the stem in the stripping operation.

6. In a machine of the character described,

in combination, stripping mechanism and means adapted to cause relative stripping movement between said mechanism and the leaves to be stripped, said stripping mechanism including a gang of leaf strippers, having stem-receiving, stripping apertures, the stripping edges of respective apertures having stripping movement lengthwise of and relative to the stem and stem-advancing movement in a direction transverse to the stem diagonally of the length of the stem in the stripping operation.

7. In a machine of the character described, in combination, a leaf stripper having a stem-receiving, stripping aperture, means for effecting relative stripping movement between said stripper and the leaf, longitudinally of the leaf, and stem-supporting devices spaced longitudinally of the stems for reception of said leaf stripper therebetween, said stem-supporting devices disposed, respectively, close to the rear and the front of said leaf stripper.

8. In a machine of the character described, in combination, a leaf stripper having a stem-receiving, stripping aperture, and means for effecting relative stripping movement between said stripper and the leaf, longitudinally of the leaf, the edges of said aperture being mounted for jam-relieving movement at an angle to that of normal stripping movement between such edges and the stem, and devices for resiliently restraining the edges of said aperture against stem-disengaging movement in the stripping operation.

9. In a machine of the character described, in combination, a leaf stripper having a stem-receiving stripping aperture, and means for effecting relative stripping movement between said stripper and the leaf, longitudinally of the leaf, the edges of said aperture being mounted for jam-relieving movement at an angle to that of normal stripping movement between such edges and the stem, and said means including mechanism for moving the edges of the stripping aperture in lines diagonal to the length of the stem in the stripping operation.

10. In a machine of the character described, in combination, a leaf stripper having a stem-receiving, stripping aperture, and means for effecting relative stripping movement between said stripper and the leaf, longitudinally of the leaf, the edges of said aperture being mounted for jam-relieving movement at an angle to that of normal stripping movement between such edges and the stem, said means including mechanism for imparting to said stripper rotative movement in the plane of the leaf and relative to the leaf in the stripping operation.

11. In a machine of the character described, in combination, a leaf stripper having a stem-receiving, stripping aperture, and means for

effecting relative stripping movement between said stripper and the leaf, longitudinally of the leaf, devices for resiliently restraining the edges of said aperture against stem-disengaging movement in the stripping operation, and said means including mechanism for moving the edges of the stripping aperture in lines diagonal to the length of the stem in the stripping operation.

12. In a machine of the character described, in combination, a leaf stripper having a stem-receiving, stripping aperture, and means for effecting relative stripping movement between said stripper and the leaf, longitudinally of the leaf, and devices for resiliently restraining the edges of said aperture against stem-disengaging movement in the stripping operation, said means including mechanism for imparting to said stripper rotative movement in the plane of the leaf and relative to the leaf in the stripping operation.

13. In a machine of the character described, in combination, a leaf stripper having a stem-receiving, stripping aperture, and means for effecting relative stripping movement between said stripper and the leaf, longitudinally of the leaf, said means including mechanism for moving the edges of the stripping aperture in lines diagonal to the length of the stem in the stripping operation, said mechanism imparting to said stripper rotative movement in the plane of the leaf and relative to the leaf in the stripping operation.

14. In a mechanism of the character described, in combination, a leaf stripper having a stem-receiving, stripping aperture, and means for effecting relative stripping movement between said stripper and the leaf, longitudinally of the leaf, the edges of said aperture being mounted for jam-relieving movement at an angle to that of normal stripping movement between such edges and the stem, said means including mechanism for imparting to said stripper rotative movement in the plane of the leaf and relative to the leaf, and for moving the edges of the stripping aperture in lines diagonal to the length of the stem in the stripping operation.

15. In a machine of the character described, in combination, a leaf stripper having a stem-receiving, stripping aperture, and means for effecting relative stripping movement between said stripper and the leaf, longitudinally of the leaf, the edges of said aperture being mounted for jam-relieving movement at an angle to that of normal stripping movement between such edges and the stem, said means including mechanism for imparting to said stripper rotative movement in the plane of the leaf and relative to the leaf in the stripping operation, and devices for resiliently restraining the edges of said

aperture against stem-disengaging movement in the stripping operation.

16. In a machine of the character described, in combination, a leaf stripper having a stem-receiving, stripping aperture, and means for effecting relative stripping movement between said stripper and the leaf, longitudinally of the leaf, devices for resiliently restraining the edges of said aperture against stem-disengaging movement in the stripping operation, said means including mechanism for moving the edges of the stripping aperture in lines diagonal to the length of the stem, and for imparting to said stripper rotative movement in the plane of the leaf and relative to the leaf in the stripping operation.

17. In a machine of the character described, in combination, stripping mechanism, and means adapted to cause relative stripping movement between said mechanism and the leaves to be stripped, said stripping mechanism including a gang of leaf strippers, strippers of which are mounted for relief movement transversely of the leaf-stems in the stripping operation and have stem-receiving, stripping apertures, flaring in a direction opposite to that of said relief movement, a device adapted yieldingly to restrain said relief movement of said strippers, a device adapted to restrain the extent of transverse movement of the stems under pressure of said strippers, and means adapted to move strippers in a recurrent path and on and off the leaves to be stripped, and means to advance leaves transversely and operative to hold the stems longitudinally stationary during said relative stripping movement.

18. In a machine of the character described, in combination, stripping mechanism, and means adapted to cause relative stripping movement between said mechanism and the leaves to be stripped, said stripping mechanism including a gang of leaf strippers, strippers of which are mounted for relief movement transversely of the leaf-stems in the stripping operation, and have stem-receiving, stripping apertures, flaring in a direction opposite to that of said relief movement, a device adapted yieldingly to restrain said relief movement of said strippers, a device adapted to restrain the extent of transverse movement of the stems under pressure of said strippers, means adapted to move said strippers in a recurrent path and on and off the leaves to be stripped, and means having leaf-accelerating and decelerating movement adapted to center the stems in said apertures for the stripping operation.

19. In a machine of the character described, in combination, stripping mechanism, and means adapted to cause relative stripping movement between said mechanism and the leaves to be stripped, said stripping mechanism including a gang of leaf strip-

pers, strippers of which are mounted for relief movement transversely of the leaf-stems in the stripping operation, and have stem-receiving, stripping apertures, flaring in a direction opposite to that of said relief movement, a device adapted yieldingly to restrain said relief movement of said strippers, a device adapted to restrain the extent of transverse movement of the stems under pressure of said strippers, means adapted to move said strippers in a recurrent path and on and off the leaves to be stripped, and means, relative to which said stripper cooperates on its relief movement, to loosen leaf jammed in the aperture.

20. In a machine of the character described, in combination, stripping mechanism, and means adapted to cause relative stripping movement between said mechanism and the leaves to be stripped, said stripping mechanism including a gang of leaf strippers, strippers of which are mounted for relief movement transversely of the leaf-stems in the stripping operation, and have stem-receiving, stripping apertures, flaring in a direction opposite to that of said relief movement, a device adapted yieldingly to restrain said relief movement of said strippers, a device adapted to restrain the extent of transverse movement of the stems under pressure of said strippers, means adapted to move said strippers in a recurrent path and on and off the leaves to be stripped, and means adapted positively to impart a relief movement to the strippers at a predetermined point or points in said recurrent path.

21. In a machine of the character described, in combination, stripping mechanism, and means adapted to cause relative stripping movement between said mechanism and the leaves to be stripped, said stripping mechanism including a gang of leaf strippers, strippers of which are mounted for relief movement transversely of the leaf-stems in the stripping operation, and have stem-receiving, stripping apertures, flaring in a direction opposite to that of said relief movement, a device adapted yieldingly to restrain said relief movement of said strippers, a device adapted to restrain the extent of transverse movement of the stems under pressure of said strippers, means adapted to move said strippers in a recurrent path and on and off the leaves to be stripped, means adapted positively to impart a relief movement to the strippers at a predetermined point or points in said recurrent path, and means adapted adjustably to vary the point or points in said path at which said positive relief movement is imparted.

22. In a machine of the character described, in combination, stripping mechanism and means adapted to cause relative stripping movement between said mechanism and the leaves to be stripped, said stripping

mechanism including a gang of leaf strippers having stem-receiving, stripping apertures, the stripping edges of respective apertures having stripping movement lengthwise of and relative to the stem and stem-advancing movement in a direction transverse to the stem diagonally of the length of the stem in the stripping operation, said means for causing relative stripping movement including a device adapted to advance leaves transversely and operative to hold the stems from lengthwise movement under the pull of the stripping movement of said stripping edges.

23. In a machine of the character described, in combination, stripping mechanism including a pair of mutually cooperative stem-drawing and gripping rolls and a gang of leaf strippers, strippers of which are mounted for relief movement, one independently of another, transversely of the stems in the stripping operation, one of the longitudinal axes of one of said rolls being free for angular movement toward and from the other transversely of the stems, and a spring adapted to restrain separating movement between said rolls in their different angular relations to each other.

24. In a machine of the character described, in combination, stripping mechanism including a pair of mutually cooperative stem-drawing and gripping rolls and a gang of leaf strippers, strippers of which are mounted for relief movement, one independently of another, transversely of the stems in the stripping operation, one of the longitudinal axes of one of said rolls being free for angular movement toward and from the other transversely of the stems, and a spring adapted to restrain separating movement between said rolls in their different angular relations to each other, respective strippers having a stem-receiving, stripping aperture in its edge, the aperture having a sinuous stripping edge.

45 25. In a machine of the character described, in combination, stripping mechanism including a pair of mutually cooperative stem-drawing and gripping rolls and a gang of leaf strippers, strippers of which are mounted for relief movement, one independently of another, transversely of the stems in the stripping operation, one of the longitudinal axes of one of said rolls being free for angular movement toward and from the other transversely of the stems, and a spring adapted to restrain separating movement between said rolls in their different angular relations to each other, respective strippers having a stem-receiving, stripping aperture in its edge, the opposite stripping edges of said aperture being at different distances from each other at different distances from said edge of said stripper.

65 26. In a machine of the character described, in combination, stripping mecha-

nism including a pair of mutually cooperative stem-drawing and gripping rolls and a gang of leaf strippers, strippers of which are mounted for relief movement, one independently of another, transversely of the stems in the stripping operation, one of the longitudinal axes of one of said rolls being free for angular movement toward and from the other transversely of the stems, and a spring adapted to restrain separating movement between said rolls in their different angular relations to each other, said gang having a series of sinuous stripping edges.

27. In a machine of the character described, in combination, stripping mechanism including a pair of mutually cooperative stem-drawing and gripping rolls and a gang of leaf strippers, strippers of which are mounted for relief movement, one independently of another, transversely of the stems in the stripping operation, one of the longitudinal axes of one of said rolls being free for angular movement toward and from the other transversely of the stems, and a spring adapted to restrain separating movement between said rolls in their different angular relations to each other, and means adapted resiliently to restrain said relief movement of said strippers.

28. In a machine of the character described, in combination, stripping mechanism including a pair of mutually cooperative stem-drawing and gripping rolls and a gang of leaf strippers, strippers of which are mounted for relief movement, one independently of another, transversely of the stems in the stripping operation, one of the longitudinal axes of one of said rolls being free for angular movement toward and from the other transversely of the stems, a spring adapted to restrain separating movement between said rolls in their different angular relations to each other, and means, including a spring for each stripper, adapted resiliently to restrain relief movement of its stripper.

29. In a machine of the character described, in combination, stripping mechanism including a pair of mutually cooperative, stem-drawing and gripping rolls, and a gang of leaf strippers having stem-receiving, stripping apertures in their edges, through which the stems are drawn by said rolls, said strippers and rolls automatically shiftable relative to each other to confine the drawing strain on the stems to tensile strain substantially free of strain transversely of the plane of cooperation of said drawing rolls.

30. In a machine of the character described, in combination, stripping mechanism including a pair of mutually cooperative, stem-drawing and gripping rolls, and a gang of leaf strippers having stem-receiving, stripping apertures in their edges, through which the stems are drawn by said

rolls, said strippers and rolls automatically shiftable relative to each other to confine the drawing strain on the stems to tensile strain substantially free of strain transversely of the plane of cooperation of said drawing rolls, one of the longitudinal axes of said rolls being free for angular movement toward and from the other transversely of the stems, and a spring operatively connected to cause resilient, gripping cooperation between said rolls in different angular relations of said axes.

31. In a machine of the character described, in combination, stripping mechanism including a pair of mutually cooperative, stem-drawing and gripping rolls, and a gang of leaf strippers having stem-receiving, stripping apertures in their edges, through which the stems are drawn by said rolls, said strippers and rolls automatically shiftable relative to each other to confine the drawing strain on the stems to tensile strain substantially free of strain transversely of the plane of cooperation of said drawing rolls, one of the longitudinal axes of said rolls being free for angular movement toward and from the other transversely of the stems, a spring operatively connected to cause resilient, gripping cooperation between said rolls in different angular relations of said axes, and a stop for limiting the extent of angular separating movement between said rolls.

32. In a machine of the character described, in combination, stripping mechanism including a pair of mutually cooperative, stem-drawing and gripping rolls, and a gang of leaf strippers having stem-receiving, stripping apertures in their edges, through which the stems are drawn by said rolls, said strippers and rolls automatically shiftable relative to each other to confine the drawing strain on the stems to tensile strain substantially free of strain transversely of the plane of cooperation of said drawing rolls, each of said rolls having a cylindrical, relatively soft, friction surface, the advance ends of said rolls being one cylindrical and the other conical, each of said ends having a stem-advancing helix.

33. In a machine of the character described, in combination, stripping mechanism including a pair of mutually cooperative, stem-drawing and gripping rolls, and a gang of leaf strippers having stem-receiving, stripping apertures in their edges, through which the stems are drawn by said rolls, said strippers and rolls automatically shiftable relative to each other to confine the drawing strain on the stems to tensile strain substantially free of strain transversely of the plane of cooperation of said drawing rolls, each of said rolls having a cylindrical, relatively soft, friction surface, the advance ends of said rolls being one cylindrical and the other

conical, each of said ends having a stem-advancing helix, one of the longitudinal axes of said rolls being free for angular movement toward and from the other transversely of the stems, a spring operatively connected to cause resilient, gripping cooperation between said rolls in different angular relations of said axes, and a stop for limiting the extent of angular separating movement between said rolls.

34. In a machine of the character described, in combination, stripping mechanism including stem drawing rolls and a leaf stripper having a stem-receiving, stripping aperture in its edge and through which aperture the stem is drawn by said rolls, said stripper mounted for independent movement transversely of the stem as the machine operates, said aperture opening through the end of said stripper and having opposite stripping edges at different distances from each other at different distances from said end of the stripper.

35. In a machine of the character described, in combination, a leaf stripper having a stem-receiving, stripping aperture, and means for effecting relative stripping movement between said stripper and the leaf, longitudinally of the leaf, the edges of said aperture being mounted for jam-relieving movement at an angle to that of normal stripping movement between such edges and the stem, said means including a pair of cooperative stem-gripping drawing rolls, said leaf stripper automatically adjustable relative to said drawing rolls to confine the drawing strain on the stem to a tensile strain substantially free of strain transversely of the plane of cooperation of said drawing rolls.

36. In a machine of the character described, in combination, a leaf stripper having a stem-receiving, stripping aperture, and means for effecting relative stripping movement between said stripper and the leaf, longitudinally of the leaf, the edges of said aperture being mounted for jam-relieving movement at an angle to that of normal stripping movement between such edges and the stem, said means including a pair of cooperative stem-gripping drawing rolls, said leaf stripper automatically adjustable relative to said drawing rolls to confine the drawing strain on the stem to a tensile strain substantially free of strain transversely of the plane of cooperation of said drawing rolls, and devices for resiliently restraining the edges of said aperture against stem-disengaging movement in the stripping operation.

37. In a machine of the character described, in combination, a leaf stripper having a stem-receiving, stripping aperture, means for effecting relative stripping movement between said stripper and the leaf, longitudinally of the leaf, the edges of said aperture being mounted for jam-relieving movement

at an angle to that of normal stripping movement between such edges and the stem, said means including a pair of cooperative stem-gripping drawing rolls, said leaf stripper 5 automatically adjustable relative to said drawing rolls to confine the drawing strain on the stem to a tensile strain substantially free of strain transversely of the plane of co-operation of said drawing rolls, and devices 10 for resiliently restraining the edges of said aperture against stem-disengaging movement in the stripping operation, said aperture opening through the end of said stripper and having opposite, sinuous, stripping 15 edges generally inclining toward each other.

38. In a machine of the character described, in combination, stripping mechanism and means adapted to cause relative stripping movement between said mechanism and the 20 leaves to be stripped, said mechanism including a gang of leaf strippers mounted for relief movement transversely of the stems in the stripping operation, and having stripping edges lying in different planes transverse to the length of the stems in the stripping operation.

39. In a machine of the character described, in combination, stripping mechanism and means adapted to cause relative 25 stripping movement between said mechanism and the leaves to be stripped, said mechanism including a gang of leaf strippers mounted for relief movement transversely of the stems in the stripping operation, and having stem-receiving, stripping apertures, the stripping edges of respective apertures having stripping movement lengthwise of and relative to the stems and stem-advancing movement in a 35 direction transverse to the stem diagonally of the length of the stem, in the stripping operation.

40. In a machine of the character described, in combination, stripping mechanism having advancing movement, means adapted 45 to cause relative stripping movement between said mechanism and the leaves to be stripped, said mechanism including a gang of leaf strippers having approaching and receding movements, separately one of another, relative to and transversely of the stems of the leaves, and means adapted resiliently to cause said separate approaching movement of each stripper.

41. In a machine of the character described, in combination, stripping mechanism having advancing movement, means adapted 55 to cause relative stripping movement between said mechanism and the leaves to be stripped, said mechanism including a gang of leaf strippers having approaching and receding movements, separately one of another, relative to and transversely of the stems of the leaves, and means adapted resiliently to cause said separate approaching movement of each stripper, said last men-

tioned means including a rail beside which said strippers advance, each stripper having a spring mounted to advance therewith into relation adapted to be stressed by said rail resiliently to cause said approaching movement in the stripping operation. 70

42. In a machine of the character described, in combination, stripping mechanism having advancing movement, means adapted to cause relative stripping movement between said mechanism and the leaves to be stripped, said mechanism including a gang of leaf strippers having approaching and receding movements, separately one of another, relative to and transversely of the stems of the leaves, means adapted resiliently to cause said separate approaching movement of each stripper, said last mentioned means including a rail beside which said strippers advance, each stripper having a spring mounted to advance therewith into relation adapted to be stressed by said rail resiliently to cause said approaching movement in the stripping operation, a chain including separate stripper-carriers loosely articulated therein, means adapted to drive said chain, and means on the respective carriers cooperative to position respective springs for cooperation with said rail. 80

43. In a machine of the character described, in combination, stripping mechanism having advancing movement, means adapted to cause relative stripping movement between said mechanism and the leaves to be stripped, said mechanism including a gang of leaf strippers having approaching and receding movements, separately one of another, relative to and transversely of the stems of the leaves, means adapted resiliently to cause said separate approaching movement of each stripper, said last mentioned means including a rail beside which said strippers advance, each stripper having a spring mounted to advance therewith into relation adapted to be stressed by said rail resiliently to cause said approaching movement in the stripping operation, and means, including a track follower on each stripper and a track, adapted positively to cause said receding movements of said strippers at a predetermined point in the path of advance thereof. 100

44. In a machine of the character described, in combination, stripping mechanism having advancing movement, means adapted to cause relative stripping movement between said mechanism and the leaves to be stripped, said mechanism including a gang of leaf strippers having approaching and receding movements, separately one of another, relative to and transversely of the stems of the leaves, means adapted resiliently to cause said separate approaching movement of each stripper, said last mentioned means including a rail beside which said strippers advance, each stripper having a spring mounted to 110

advance therewith into relation adapted to be stressed by said rail resiliently to cause said approaching movement in the stripping operation, a chain including separate stripper-carriers loosely articulated therein, means adapted to drive said chain, means on the respective carriers to position respective springs for cooperation with said rail, and means, including a track follower on each stripper and a track, adapted positively to cause said receding movements of said strippers at a predetermined point in the path of advance thereof.

45. In a machine of the character described, in combination, stripping mechanism having advancing movement, and means adapted to cause relative stripping movement between said mechanism and the leaves to be stripped, said mechanism including a gang of depending leaf strippers separately movable in vertical planes and having track followers, a track having sections in different horizontal planes beside which said followers move, a stripper depressing rail, and springs, one on each stripper, adapted resiliently to transmit pressure from said rail to said strippers through said springs.

46. In a machine of the character described, in combination, stripping mechanism having advancing movement, means adapted to cause relative stripping movement between said mechanism and the leaves to be stripped, said mechanism including a gang of depending leaf strippers separately movable in vertical planes and having track followers, a track having sections in different horizontal planes beside which said followers move, a stripper depressing rail, springs, one on each stripper, adapted resiliently to transmit pressure from said rail to said strippers through said springs, and means adapted, at will, to vary the elevation of a section of said track for positively elevating said strippers during a portion of their stripping operation.

47. In a machine of the character described, in combination, stripping mechanism having advancing movement, and means adapted to cause relative stripping movement between said mechanism and the leaves to be stripped, said stripping mechanism including two gangs of leaf strippers, the strippers of each gang movable in separate recurrent paths and on and off the leaves to strip different portions thereof.

48. In a machine of the character, described, in combination, stripping mechanism having advancing movement, and means adapted to cause relative stripping movement between said mechanism and the leaves to be stripped, said stripping mechanism including two gangs of leaf strippers, the strippers of each gang movable in separate recurrent paths and on and off the leaves, means to cause the advance movement

of one of said gangs to be rearwardly inclined relative to that of advance of the other gang.

49. In a machine of the character described, in combination, stripping mechanism having advancing movement, means adapted to cause relative stripping movement between said mechanism and the leaves to be stripped, said stripping mechanism including two gangs of leaf strippers, the strippers of each gang movable in separate recurrent paths and on and off the leaves, said means including a leaf-holding and advancing device disposed in front of the advancing path of one of said gangs, and a stem-drawing device disposed in rear of the advancing path of the other gang.

50. In a machine of the character described, in combination, stripping mechanism having advancing movement, means adapted to cause relative stripping movement between said mechanism and the leaves to be stripped, said stripping mechanism including two gangs of leaf strippers, the strippers of each gang movable in separate recurrent paths and on and off the leaves, said means including a leaf holding and advancing device disposed in front of the advancing path of one of said gangs, and a stem-drawing device disposed in rear of the advancing path of the other gang, the advancing movement of one of said gangs being rearwardly inclined relative to that of said leaf holding and advancing device and of said other gang.

51. In a machine of the character described, in combination, leaf stripping mechanism including a plurality of leaf strippers having advancing movement in the stripping field, and a leaf holding and advancing device and a stem-drawing device alongside the paths of advance of said strippers, said leaf holding and advancing device including a movable, endless series of leaf grippers, mounted for pivotal displacement from operative position over the leaves, and means for securing said series in operative position.

52. In a machine of the character described, in combination, leaf stripping mechanism including a plurality of sets of leaf strippers having advancing movement in the stripping field, a leaf holding and advancing device and a stem-drawing device alongside the paths of advance of each of said sets of strippers, said leaf holding and advancing device including a leaf advancing and supporting belt, and two endless series of leaf grippers between which said supporting belt is gripped.

53. In a machine of the character described, in combination, leaf stripping mechanism including a plurality of leaf strippers having advancing movement in the stripping field, a leaf holding and advancing device and a stem-drawing device alongside the paths of advance of said strippers, said leaf

holding and advancing device including a leaf advancing and supporting belt, two endless series of leaf grippers between which said supporting belt is gripped, a frame piece 5 detachably bolted to the frame of the machine, and having sprocket wheels and chain carrying one of said series of grippers, and a shaft for driving one of said sprocket wheels, said frame piece being pivoted on 10 said shaft.

54. In a machine of the character described, in combination, leaf stripping mechanism including a plurality of leaf strippers having advancing movement in the stripping field, a leaf holding and advancing device and a stem-drawing device alongside the paths of 15 advance of said strippers, and coacting therewith, said leaf holding and advancing device including an endless series of traveling leaf 20 gripper blocks, a pivotally mounted frame piece, and sprocket wheels and a chain, mounted in said frame, said blocks carried by said chain, a driving shaft for one sprocket wheel, upon which shaft said frame 25 is pivoted and a leaf separating and advancing device comprising two endless belts adapted to grip the stems of leaves therebetween, one belt being of frictional material 30 and driven by a belt pulley on said driving shaft, said separating device delivering to 35 said holding and advancing device.

55. In a machine of the character described, in combination, leaf stripping mechanism including a plurality of leaf strippers having advancing movement in the stripping field, a leaf holding and advancing device and a stem-drawing device alongside the paths of 40 advance of said strippers, said leaf holding and advancing device including an endless series of traveling, leaf gripper blocks, a leaf 45 separating and advancing mechanism disposed to advance the leaves to the leaf holding and advancing mechanism, said leaf separating and advancing mechanism including two 50 endless belts between which the stems of the leaves are gripped, and means for driving one 55 separating belt at greater speed than the other.

56. In a machine of the character described, in combination, leaf stripping mechanism including a plurality of leaf strippers having advancing movement in the stripping field, and a leaf holding and advancing device and a stem-drawing device alongside the paths 60 of advance of said strippers, said leaf holding and advancing device including an endless series of traveling, leaf gripper blocks, a leaf 65 separating and advancing mechanism disposed to advance the leaves to the leaf holding and advancing mechanism, said leaf separating and advancing mechanism including two 70 endless belts, one of greater friction than the other, between which the stems of the leaves are gripped, and means for driving 75 the greater friction belt at greater speed than

the other, and a plurality of parallel, endless belts of soft frictional material disposed to support the leaves and advance them to said leaf separating and advancing mechanism.

57. In a machine of the character described, in combination, leaf stripping mechanism including a plurality of leaf strippers having advancing movement in the stripping field, a leaf holding and advancing device and a stem drawing device alongside the paths of 80 advance of said strippers, said leaf holding and advancing device including an endless series of traveling, leaf gripper blocks, a leaf 85 separating and advancing mechanism disposed to advance the leaves to the leaf holding and advancing mechanism, said leaf separating and advancing mechanism including two 90 endless belts, one of greater friction than the other, between which the stems of the leaves are gripped, means for driving the greater 95 friction belt at greater speed than the other, a plurality of parallel, endless belts of soft frictional material disposed to support the leaves and advance them to said leaf separating and advancing mechanism, and means including one or more air conduits disposed to discharge air against the butts of the leaves to accelerate their advance to the leaf separating and advancing mechanism.

58. In a machine of the character described, in combination, leaf stripping mechanism including a plurality of leaf strippers having advancing movement in the stripping field, and a leaf holding and advancing device and a stem drawing device alongside the paths 100 of advance of said strippers, said leaf holding and advancing device including an endless series of travelling, leaf gripper blocks, a leaf 105 separating and advancing mechanism disposed to advance the leaves to the leaf holding and advancing mechanism, said leaf separating and advancing mechanism including two 110 endless belts between which the stems of the leaves are gripped, one of said leaf separating belts mounted for rocking movement in a plane transverse of the leaves.

59. In a machine of the character described, in combination, leaf stripping mechanism including a plurality of leaf strippers having advancing movement in the stripping field, and a leaf holding and advancing device and a stem drawing device alongside the paths of advance of said strippers, a table, a plurality of endless, leaf-supply belts at one end of said table, supplemental endless, leaf advancing belts in advance of said supply belts, a soft, endless belt of frictional material in superposed relation to one of said supplemental belts and cooperating therewith to grip intervening leaves, said leaf holding and advancing device including two endless series of grippers, one series immediately above and the other immediately below one of said supplemental belts, the path of one series of said grippers being in overlapping 120 125 130

relation to that of said belt of frictional material.

60. In a machine of the character described, in combination, leaf stripping mechanism including a plurality of leaf strippers having advancing movement in the stripping field, a leaf holding and advancing device and a stem drawing device alongside the paths of advance of said strippers, a table, a plurality of endless, leaf-supply belts at one end of said table, supplemental endless, leaf-advancing belts in advance of said supply belts, a soft, endless belt of frictional material in superposed relation to one of said supplemental belts and cooperating therewith to grip intervening leaves, said leaf holding and advancing device including two endless series of gripper blocks, one series immediately above and the other immediately below one of said supplemental belts, a rotatable driving shaft beneath said table, means including belt pulleys on said shaft for actuating said supplemental belts, a second rotatable driving shaft above said table, and means operated from said second shaft to drive one of said series of gripper blocks and said belt of soft frictional material.

61. In a machine of the character described, in combination, leaf stripping mechanism including a plurality of leaf strippers having advancing movement in the stripping field, and a leaf holding and advancing device and a stem drawing device alongside the paths of advance of said strippers, a table, a plurality of endless, leaf-supply belts at one end of said table, supplemental endless, leaf-advancing belts in advance of said supply belts, a soft, endless belt of frictional material in superposed relation to one of said supplemental belts and cooperating therewith to grip intervening leaves, said leaf holding and advancing device including two endless series of gripper blocks, one series immediately above and the other immediately below one of said supplemental belts, the paths of one series of said gripper blocks being in overlapping relation to that of said belt of frictional material, said belt of frictional material being mounted for rocking movement transversely of the plane of its cooperative supplemental belt, a rotatable driving shaft beneath said table, means including belt pulleys on said shaft for actuating said supplemental belts, a second rotatable driving shaft above said table, and means operated from said second shaft to drive one of said series of gripper blocks and said belt of soft frictional material.

62. In a machine of the character described, in combination, leaf stripping mechanism including a plurality of leaf strippers having advancing movement in the stripping field, a leaf holding and advancing device and a stem drawing device alongside the paths of advance of said strippers, a table, a plurality of endless, leaf-supply belts at one end of said table, supplemental endless, leaf-advancing belts in advance of said supply belts, a soft, endless belt of frictional material in superposed relation to one of said supplemental belts and cooperating therewith to grip intervening leaves, said leaf holding and advancing device including two endless series of gripper blocks, one series immediately above and the other immediately below one of said supplemental belts, the paths of one series of said gripper blocks being in overlapping relation to that of said belt of frictional material, said belt of frictional material being mounted for rocking movement transversely of the plane of its cooperative supplemental belt.

63. In a machine of the character described, in combination, a rocker, belt pulleys carried by said rocker at each side of the rocking axis, one or more endless, leaf gripping, relatively soft, rubber belts, round in cross-section supported by said pulleys, a flat belt adapted to cooperate with said rubber belt to grip leaves therebetween, and means adapted to drive said rubber belt at greater speed than said flat belt.

64. In a machine of the character described, in combination, leaf holding and advancing mechanism comprising a leaf advancing belt, and two endless series of advancing gripper blocks disposed to grip said advancing belt therebetween.

65. In a machine of the character described, in combination, leaf holding and advancing mechanism comprising a leaf advancing belt, and two endless series of advancing gripper blocks disposed to grip said advancing belt therebetween, one series of gripper blocks being relatively hard and the other relatively soft.

66. In a machine of the character described, in combination, leaf holding and advancing mechanism comprising a leaf advancing belt, and two endless series of advancing gripper blocks disposed to grip said advancing belt therebetween, one series of gripper blocks being relatively hard and the other relatively soft, a sprocket chain to which said gripper blocks are attached, means to drive said chain, and means, including springs, interposed between the runs of one of said chains for resiliently effecting gripping of the leaves between said series of gripper blocks and said advancing belt.

67. In a machine of the character described, in combination, stripping mechanism including a pair of mutually cooperative, stem-drawing and gripping rolls, a gang of leaf strippers having stem-receiving, stripping apertures in their edges, through which the stems are drawn by said rolls, said strippers and rolls automatically shiftable relative to each other to confine the drawing strain on the stems to tensile strain substantially free

of strain transversely of the plane of co-operation of said drawing rolls, each of said rolls having a cylindrical, relatively soft, friction surface, the advance ends of said rolls being one cylindrical and the other conical, each of said ends having a stem advancing helix, one of the longitudinal axes of said rolls being free for angular movement toward and from the other transversely of the stems, 10 a spring operatively connected to cause resilient, gripping cooperation between said rolls in different angular relations of said axes, a stop for limiting the extent of angular separating movement between said rolls, and 15 means, including two ledger blades for supporting said stem close alongside the front and the rear of said stripper, in the stripping operation.

68. In a machine of the character described, 20 in combination, a leaf stripper having a stem-receiving, stripping aperture, mechanism for advancing said stripper and for effecting relative stripping movement between said stripper and the leaf, longitudinally of the leaf, and a leaf-centering device having leaf-accelerating movement relative to a leaf stripper at one point in the path of the strippers, and leaf-decelerating movement relative thereto at a subsequent point in said path.

69. In a machine of the character described, 25 in combination, a series of leaf strippers having stem-receiving stripper apertures and movable in a recurrent path through the field of stripping and toward and from the leaves transversely of the stems, and a driven, leaf-centering roll alongside said path, the peripheral speed of said centering roll being greater than that of advance of said leaf strippers.

70. In a machine of the character described, 30 in combination, a series of leaf strippers having stem-receiving stripper apertures and movable in a recurrent path through the field of stripping and toward and from the leaves transversely of the stems, and a driven, leaf-centering roll alongside said path, the peripheral speed of said centering roll being greater than that of advance of said leaf strippers, the periphery of said roll overlapping stem-engaging position of the apertures of leaf strippers adjacent said roll.

71. In a machine of the character described, 35 in combination, a series of leaf strippers having stem-receiving stripper apertures and movable in a recurrent path through the field of stripping and toward and from the leaves transversely of the stems, and two driven, leaf-centering rolls alongside said path, one in advance of the other, the periphery of each of said rolls overlapping stem-engaging position of the apertures of leaf strippers adjacent said respective rolls, the peripheral speed of said centering rolls being greater than that of advance of said leaf strippers.

72. In a machine of the character described, 40 in combination, leaf stripping mechanism including stem-drawing mechanism, and means located in advance of said drawing mechanism adapted, at a predetermined point in the length of the stem, to weaken the stem to be drawn by said drawing mechanism.

73. In a machine of the character described, 45 in combination, leaf stripping mechanism including stem-drawing mechanism, and means adapted, at a predetermined point in the length of the stem, to weaken the stem to be drawn by said drawing mechanism, leaf supporting and advancing mechanism, said 50 weakening means including a stem cutter facing the blade of the advancing leaf and spaced from the immediately opposite leaf support.

74. In a machine of the character described, 55 in combination, leaf stripping mechanism including stem-drawing mechanism, leaf holding and advancing mechanism, and a stem cutter facing the blade of the leaf held by said leaf holding and advancing mechanism and located in advance of said drawing mechanism to preparatorily weaken the stem.

75. In a machine of the character described, 60 in combination, leaf stripping mechanism including stem-drawing mechanism, means adapted, at a predetermined point in the length of the stem, to weaken the stem to be drawn by said drawing mechanism, leaf supporting and advancing mechanism, said 65 weakening means including a stem cutter facing the blade of the advancing leaf and spaced from the immediately opposite leaf support, and means mounting said cutter for being shifted lengthwise of the leaf.

76. In a machine of the character described, 70 in combination, leaf stripping mechanism including stem-drawing mechanism, a lever having an arm pivotally movable toward and from the leaf, a rotative, stem cutting disk journaled on said arm, a frame piece, a lever supporting bracket adjustable on said frame piece to different positions lengthwise of the leaf, means to secure said lever in different positions of its pivotal movement, and means adapted to rotate said disk.

77. In a machine of the character described, 75 in combination, a gang of strippers having stem-receiving, leaf stripping apertures, a track adapted to support said strippers and along which they advance, said track including a stripper-supporting track-section adjustable to different positions.

78. In a machine of the character described, 80 in combination, a gang of strippers having stem-receiving leaf stripping apertures, a track adapted to support said strippers and along which they advance, said track including a stripper-supporting track-section adjustable to different positions.

section adjustable to different positions, and means operable from the exterior of the machine for adjusting said section.

79. In a machine of the character described, in combination, a gang of strippers having stem-receiving, leaf stripping apertures, a track adapted to support said strippers and along which they advance, said track including a plurality of succeeding track sections pivoted together and adjustable to different angular relations with each other, and means for maintaining continuity of said track sections with the main track in different positions of adjustment.

80. In a machine of the character described, in combination, a gang of strippers having stem-receiving, leaf stripping apertures, a track adapted to support said strippers and along which they advance, said track including a pivoted, stripper-supporting track-section, a rotatively adjustable shaft having an arm, a link joining said arm and track-section, and means to secure said shaft in adjusted position.

81. In a machine of the character described, in combination, a carrier including a block, a stripper having a haft slidably supported on said block, a follower pin slideable on said carrier, and a spring interposed between said haft and pin.

82. In a machine of the character described, in combination, a carrier including a block, a stripper having a haft slidably supported on said block, said carrier including an extension having an aperture, a hollow follower pin slideable in said aperture, a pin on said haft extending into said first named pin, and a spring secured to said haft and extending into said hollow pin.

83. In a machine of the character described, in combination, a carrier including a block, a stripper having a haft slidably supported on said block, said carrier including an extension having an aperture, a hollow follower pin slideable in said aperture, a pin on said haft extending into said first named pin, and a spring secured to said haft and extending into said first named pin, said haft having a track follower, said stripper including a blade having a stripper aperture in its edge, the edge of said aperture being sinuous.

84. In a machine of the character described, in combination, leaf advancing mechanism and stripping mechanism, including a plurality of separate stripper blades having advancing movements with the leaves and each mounted to ride independently and loosely on the leaves in the stripping operation.

85. In a machine of the character described, in combination, leaf advancing mechanism and stripping mechanism, including a plurality of sets of separate stripper blades having advancing movements with the leaves and each blade mounted to ride independently and loosely on the leaves in the stripping opera-

tion, and means, adapted simultaneously to impart to said sets of blades advancing movement in directions diverging relative to each other in the stripping field, to effect butting and stemming of an advancing leaf.

86. In a machine of the character described, in combination, leaf stripping mechanism including a leaf stripper having a stem-receiving, stripping aperture, said stripper mounted for relief movement under the pressure of a leaf to be stripped, means adapted positively to effect movement of said stripper in a relieving direction, and an aperture-clearer adapted yieldingly to oppose movement of leaf material with the stripper in relief movement of the stripper.

In testimony whereof he hereunto affixes his signature.

LOUIS H. ZEUN.
